TO THE SYMINGTON COMPANY, OF NEW YORK, N. Y., A CORPORATION OF MARY-
LAND

DRAFT RIGGING

Application filed March 19, 1925, Serial No. 16,649. Renewed February 10, 1931.

This invention relates to draft rigging for railway cars.

The principal object of the invention, generally considered, is to provide a pivotally connected coupler and yoke in railway draft rigging, said yoke being preferably of the vertical type with web portions connecting the forward ends of the arms thereof, said web portions serving to limit the pivotal motion between the coupler and yoke, and means attached to the draft sills for reinforcing said webs upon such pivotal motion.

Another object of our invention is to provide, in a railway draft rigging, a coupler and a yoke with a hooded end on the yoke surrounding the stem of the coupler, and an upright key intersecting said hood and stem for permitting pivotal motion between coupler and yoke, said hooded portion on the yoke serving to limit the pivotal motion, means being provided on the draft sills adapted to engage the hooded portion of the yoke and reinforce the same.

A further object of our invention is the provision of a form of yoke for railway draft rigging, which yoke is of a type designated as vertical and provided with forwardly extending arms formed with registering slot portions for receiving a pivotal member, said arms being connected at their forward ends by integral side walls, thereby forming a hollow, open-ended portion adapted to receive a coupler stem and limit pivotal motion between it and the yoke.

A still further object of our invention is the provision of a draft rigging stop member which is adapted to perform the double function of engaging and acting as a stop member for cushioning mechanism, and also serve as a centering and reinforcing abutment member for the hooded portion of a yoke with which it is adapted to be employed.

Other objects and advantages of the invention relating to the particular construction and arrangement of parts, will become apparent as the description proceeds.

In the drawings, wherein an embodiment of the invention is illustrated, the scope whereof is pointed out in the claims:

Figure 1 is a view, partially in plan and

partially in longitudinal section, of the center or draft sills and associated parts of a car underframe in combination with draft rigging embodying our invention.

Figure 2 is a central longitudinal vertical 55 sectional view of the construction shown in Figure 1, parts of the mechanism, however, being shown in side elevation.

Figure 3 is an end view of the construction shown in Figure 1.

Figure 4 is a transverse vertical section on the line 4—4 of Figure 1, and looking in the direction of the arrows.

Figure 5 is a transverse vertical sectional view taken on the line 5—5 of Figure 1, and 65 looking in the direction of the arrows.

Figure 6 is a top plan view of the lower supplemental guide or carry iron member.

In the drawings, in which like parts are designated by like reference characters, the 70 numeral 1 designates the center or draft sills of a car, 2 the rear portion or stem of a coupler, and 3 a yoke member.

In the present embodiment the yoke 3 is 75 illustrated as of the vertical type and formed with forwardly extending arms 4 and 5 between which cushioning mechanism, diagrammatically illustrated by dot and dash lines, is embraced. The cushioning mechanism is here shown provided with a front follower member 6 and a rear follower member 7, said rear follower member abutting against the rear portion 8 of the yoke which joins the arms 4 and 5 thereof.

For transmitting forces from the cushioning mechanism to the draft sills 1, rear stop members 9 and 10, which may be of ordinary construction, and front stop members 11 and 12, of special construction to be hereinafter described in detail, are provided. The rear stop members 9 and 10 serve as abutments for the rear follower member 7 and are preferably provided with longitudinally extending faces 13 and 14, between which the yoke 95 85 is centered.

The forward portions of the arms 4 and 5 of the yoke are provided with registering slots 15 and 16 for the reception of an upright or substantially vertical key 17, serving to operatively and pivotally connect the 100

coupler and yoke members. The coupler stem 2 is likewise formed with a slot 18 through which the key 17 passes. The slot 18 is preferably of approximately the same size as the key 17 so that a fairly close fit is obtained, whereas the slots 15 and 16 in the yoke arms are preferably flared rearwardly, as illustrated, so that the key is permitted to pivot or angle about its forward edge for allowing corresponding pivotal motion between the coupler and yoke. For limiting such pivotal motion the forward portions of the arms 4 and 5 of the yoke, which are preferably widened and increased in depth, as illustrated at 19, to compensate for the slots 15 and 16 therein, are connected at their corresponding side edges by means of upright or substantially vertical web portions 20 and 21, which portions are preferably formed integrally with the yoke arms and extend in substantially longitudinal planes parallel to each other. These web portions 20 and 21 as will be obvious, are engaged by the rearward portion of the coupler stem upon angling or pivotal motion between the coupler and yoke and thereby serve to limit said angling motion.

In order to prevent breakage of these webs 20 and 21, or obviate the necessity of making such webs unduly heavy, the stop members 11 and 12 are formed with stop faces 22, 23, 24 and 25, which extend substantially parallel to and closely embrace the web portions 20 and 21 on the yoke. These stop faces, as most clearly illustrated in Figure 4, are formed as flanged extensions on the rib or reinforcing web portions 26, 27, 28 and 29 of the forward stop members 11 and 12. It will therefore be apparent that the stop faces 22, 23, 24 and 25, which are engaged by and serve to limit the movement of and reinforce the web portions 20 and 21 on the yoke 3, are preferably integrally connected with the base or main attaching web portion 30 of the respective stop member or casting, by the web portions 26, 27, 28 and 29, respectively. The stop faces 22, 23, 24 and 25 do not need to extend the full length of the stop member, and, as shown in Figure 1, the connecting web portions, therefore, are tapered from the ends of said stop faces and gradually merge into the main web 30 of the stop member. All of said stop faces, and their connecting webs, are jointed at the rear end of the stop member by the stop face 31, which is engaged directly by the front follower 6.

Although four stop faces for each coupler web are shown on each stop casting, it is obvious that we do not wish to be limited to this number, as one or any convenient number of such faces may be used. The stop faces are here shown as separated for the more convenient removal of the cores, but it is obvious that they may be made continuous or at least partly continuous, if desired. As illustrated,

however, the said stop faces serve to very materially strengthen the resisting power of the webs 20 and 21 on the yoke when said webs are engaged by the end of the coupler or coupler stem upon pivotal motion thereof. 70

The yoke member, as illustrated, may be supported by a yoke support or carry iron 32, near the rear end thereof, and a carry iron 33, near the forward end thereof. Said carry iron 33 also serves as a support for 75 the key 17, as will be understood. An upper yoke guide 34 is preferably provided adjacent the rear end of the yoke. These members 32 and 33 may be connected to the center or draft sills by bolts or other desired fastening means 35. The top guide 34, however, is preferably connected to the top cover plate 36 by means of rivets or other connecting means 37, as illustrated most clearly in Figure 5. 85

The other portions of the draft rigging and cooperating parts of the car underframe may be of any ordinary or desired construction. For example, the end sill 37^a is shown as of angle form and connected to the top cover plate 36 in any desired manner. A striking casting is shown at 38 and a coupler carry iron at 39 connected to the striking casting by means of bolts or studs 40 which pass through the ears 41 on the carry iron 95 and through the downwardly projecting flange 42 of the striking casting. 90

Although in the present embodiment of the invention, the yoke is shown as of the vertical type and the coupler is pivotally connected thereto by means of an upright key, it is obvious that we do not wish to be restricted to such construction, as a yoke of a different type may be employed and the pivotal connection between it and the coupler may be of a different character. By virtue of our invention, however, we have provided means by which the upright webs on one of said connected members, which serve to limit the pivotal motion between it and the other member, are efficiently reinforced by means of stop castings positioned on either side of the pivotal connection, which stop castings have cooperating faces which bear against said limiting web portions and reinforce the same as well as provide for transmitting draft forces to the sills. 110 115 120

Having now described our invention, what we claim is:

1. In a draft rigging, the combination with draft sills, of a coupler, a yoke pivotally connected thereto and provided with means for limiting said pivotal motion, and means on the draft sills, adjacent said limiting means and presenting flat faces thereto for reinforcing the same. 120 125

2. In a draft rigging, the combination with draft sills, of a coupler, a yoke pivotally connected thereto and provided with integral walls on either side of the coupler for limit- 130

ing said pivotal motion, and means on the draft sills, adjacent said walls presenting flat faces adapted to be engaged thereby for reinforcing the same.

5 3. In a draft rigging, the combination with draft sills, of a coupler, a yoke, an upright key extending through forward portions of the yoke and a rearward portion of the coupler for pivotally connecting said members, 10 one of said members being formed with portions extending on both sides of the other member for limiting pivotal motion and means on said draft sills presenting flat faces for engaging and reinforcing said limiting 15 means.

4. In a draft rigging, the combination with draft sills, of a coupler, a yoke, an upright key extending through forward portions of the yoke and a rearward portion of the coupler for pivotally connecting said members, 10 one of said members being formed with upright wall portions extending on both sides of the other member for limiting pivotal motion and stop members on said draft sills provided with flat wall portions adapted to engage the upright wall portions for reinforcing said limiting means.

5. In a draft rigging, the combination with draft sills, of a coupler, a yoke provided with 20 forwardly extending arms and a hooded forward portion surrounding the rear portion of the coupler, said hooded portion being formed by integral wall portions connecting the side edges of the forward ends of the yoke arms, 25 an upright key member pivotally connecting said coupler and yoke, said coupler being engaged by the wall portions of the yoke upon pivotal motion therebetween, and stop castings on the draft sills provided with walls 30 extending substantially parallel to and adapted to contact with said yoke wall portions, upon pivotal motion, and reinforce the same.

6. In a draft rigging, the combination with draft sills, of a coupler, a yoke, cushioning 40 mechanism within the same, stop members connected to said sills for transmitting thereto, through the cushioning mechanism, the forces delivered to said coupler, a substantially vertically-arranged key operatively 45 connecting said yoke and coupler and allowing pivotal motion therebetween, said yoke being provided with wall portions on either side of the coupler for limiting pivotal motion of the coupler with respect thereto, and 50 wall portions on said stop members adjacent the wall portions on the yoke, for engaging and reinforcing the same.

7. In a draft rigging, in combination with draft sills, a coupler with a rearwardly extending stem, a vertical yoke with forwardly directed arms extending above and below the coupler stem, a key intersecting said arms and stem for pivotally connecting the same, integral web portions connecting the corresponding side edges of the yoke arms for lim-

iting the pivotal movement between coupler and yoke and stop members connected to the sills on either side of the web portions, said stop members being provided with wall portions under some circumstances adapted to engage and reinforce the web portions on the yoke, upon engagement of the coupler stem therewith.

8. In a draft rigging, in combination with draft sills, a coupler with a rearwardly extending stem, a vertical yoke with forwardly directed arms extending above and below the coupler stem, cushioning mechanism within the yoke, a key intersecting said arms and stem for pivotally connecting the same, integral web portions connecting the corresponding side edges of the yoke arms for limiting the pivotal movement between coupler and yoke, and stop members connected to the sills on either side of the web portions, 80 said stop members being adapted to transmit, through the cushioning mechanism, the forces delivered to the coupler, and provided with wall portions in some instances adapted to engage and reinforce the web portions on the 85 yoke, upon engagement of the coupler stem therewith.

9. A draft rigging stop member provided with a web for attachment to a draft sill, a wall for engagement with cushioning mechanism, and another wall, longitudinally extending, parallel to and spaced from the attaching web, for engagement with the side of a cooperating yoke.

10. A draft rigging stop member provided with a web for attachment to a draft sill, a wall disposed substantially at right angles thereto for engagement with cushioning mechanism, and a plurality of longitudinally disposed wall portions substantially parallel 100 to the attaching web, for engagement with the side of a cooperating yoke and adapted to reinforce the same.

11. In a draft rigging, in combination with draft sills, a coupler, a yoke, a vertical key 110 connecting said coupler and yoke and permitting pivotal motion therebetween, side walls on said yoke for limiting the pivotal motion of the coupler with respect thereto, and stop members formed with webs connected to the draft sills and walls spaced from said connecting webs and closely embracing the side walls of the yoke for reinforcing said side walls upon engagement therebetween.

12. In a draft rigging, in combination with draft sills, a coupler, a yoke pivotally connected thereto and provided with parallel walls embracing the butt of said coupler, and stop members positioned on either side of said yoke and formed with webs connected to the respective draft sills and walls spaced from said webs, parallel thereto and closely embracing the adjacent walls of the yoke for reinforcing said walls upon engagement therewith.

13. In a draft rigging, in combination with draft sills, a coupler, a yoke pivotally connected thereto and formed with integral walls on either side of said coupler for limiting pivotal motion therebetween, and a stop member on either side of said walls connected to the respective draft sill by means of a web thereof and formed with a wall normally parallel to the integral walls on the yoke,
10 closely spaced with respect thereto and correspondingly spaced from the web connecting said stop to the draft sill for reinforcing the walls of the yoke upon engagement of said walls therewith.
- 15 14. In a draft rigging, in combination with draft sills, a coupler, a yoke, an upright key extending through forward portions of the yoke and a rearward portion of the coupler for connecting said members while permitting horizontal angling therebetween, one of said members being formed with walls extending on both sides of the other member for limiting relative angling, and a stop member connected to the sills on either side of said
20 walls, formed with a wall disposed substantially at right angles to said sills for engagement with associated cushioning mechanism and a plurality of longitudinally disposed wall portions closely positioned with respect
25 to the walls for limiting pivotal motion between coupler and yoke and directed substantially parallel to said draft sills.

In testimony whereof we affix our signatures.
